UNITED STATES PATENT OFFICE.

JOHN WHYTE, OF EVERETT, WASHINGTON.

COUNTERSINK ATTACHMENT FOR BITS.

1,072,543.

Specification of Letters Patent. Patented Sept. 9, 1913.

Application filed August 1, 1910. Serial No. 575,005.

To all whom it may concern:

Be it known that I, JOHN WHYTE, a citizen of the United States, residing at Everett, State of Washington, have invented a new and useful Improvement in Countersink Attachments for Bits, of which the following is a specification.

My invention relates to an improvement in countersink attachment for bits, and comprises the novel parts and combinations of parts which will be hereinafter described and particularly pointed out in the claims.

The object of my invention is, in general, to improve and simplify such devices, and in particular to provide a device of this character which will do smooth work without roughening or breaking the wood, and one also which will have sufficient resistance by the time it has made the desired depth of countersink, that it will overhaul the bit, that is, free the screw which serves to draw the bit into the wood.

In the drawings I have shown my invention in the form which is now preferred by me.

Figure 1 is an elevation or side view of my device. Fig. 2 is an end view of the cutting end of the form of my device shown in Fig. 1. Figs. 3 and 4 are like views of my device having a modified form of cutting teeth.

In the countersunk attachments which have heretofore been generally employed, one of the most serious objections is their tendency to roughen the surface of the board outside of the countersunk area. Another principal objection is that they will not, with certainty, free the bit from its in-drawing tendency, and, therefore, the bit and its attached countersink will keep on boring into the wood, and the countersunk area will often be made larger or deeper than is intended or desired. The result is invariably, countersinks of varying size and depth.

The common countersinks quite generally have their teeth so shaped that they are very small or almost reduced to nothing at the margin of the central bore which receives the bit. It is one of my objects to so shape the teeth that they will have a pronounced tooth shape at this inner margin, whereby they will cleanly cut the borings produced by the bit as well as cut the wood within the area of the countersink; this shape is clearly shown in Figs. 1 and 3. In these two figures no attempt has been made to show the

outline of any teeth which lie in the rear-most half of the device, for to do so would complicate the drawing. These figures may thus be considered as being an elevation of the outer side of one half of the device, the plane of cut being a central longitudinal one.

The device consists of a tubular body adapted to fit over a bit provided with cutting teeth upon one end which is beveled and forms the countersink. It is also provided with a set screw or other convenient means for securing it in place upon the bit.

The cylindrical body 1 has a central bore 10 of such size as to fit over a bit of the size 70 with which it is intended to use it. The lower or cutting end is beveled to form a cone having the same angle as that desired for the sides of the countersink. In this conical end are formed the cutting teeth, 75 these extending with their axes substantially parallel with the outer surfaces of the cone. The outline shape of these teeth may be varied somewhat. I have found that the best results are obtained when their depth 80 is relatively considerable, and also prefer that their surfaces be at unequal angles for opposite sides of the same teeth. As I have shown them the channel 3 between teeth has one side, 31, which is the advancing side of 85 the teeth, at rather a sharp angle, approaching a perpendicular to the plane of revolution. The opposite side 30 is at a much flatter angle. This form makes of each tooth a chisel which will smoothly and cleanly cut 90 the wood, avoiding splintering or breaking out of particles extending beyond the margin of the countersink.

I prefer that the straight sides of the body 1 be provided with channels 2 in line 95 with the channels 3 in the conical end. These I have herein shown as having their sides at equal angles. Above the grooved or channeled sides I bore and thread the wall and insert a set screw 5, by which the device 100 may be secured in place upon a bit.

In Figs. 3 and 4 I have shown a modified form of construction, the modification consisting in making the toothed end with two different slopes or cones, a cone 6 of sharper 105 angle being interposed between the terminal cone and the cylindrical portion 1. This intermediate cone 6 has grooves therein forming teeth, which may be a continuation of the grooves 2 in the cylindrical portion, or of 110 the grooves 3 which form the cutting teeth. I have shown them as continuations of the

grooves 2. This modification is of value where it is desired to countersink to such depth that the head of the screw will be sufficiently beneath the surface to permit the 5 insertion of a wooden plug, thereby hiding the screw head. The upper cone 6 forms a smooth walled recess of truly rotative surface, for which plugs may be made which will accurately fit even if they vary in depth. 10 As a result of the difference in the tooth angles in the tip section and in the next section above, being the cylindrical body section of Fig. 1 and the cone frustum 6 of Fig. 3, the bottom of the channels 3 in the tip section extend upward into one face of the section above, as is clearly seen in Figs. 1 and 3. The under side of the face thus formed at the lower end of the upper groove creates a stop which, by impeding the free 15 escape of the cuttings, prevents further entrance of the bit or countersink into the wood.

I have found that a countersink having the form of teeth shown will cut freely until 20 it reaches a certain depth corresponding to that desired for the countersink, and will by this time produce a resistance or backward pull upon the bit sufficient to relieve or free the indrawing screw of the bit from 25 its hold upon the wood, thus stopping the advance of the bit into the wood. It thus acts as a stop to limit the depth of the hole made by the bit.

What I claim as my invention is—

30 1. A countersink for wood having a coned end provided with teeth having their advancing face at a relatively greater angle

to the face of the countersink than their other face, the section of the countersink next above said coned end being toothed 40 with the outer points of the teeth matching with the points of the cutting teeth of the coned end, the two faces of these upper teeth being of substantially like angle, the bottom angles of the teeth upon said coned end extending into one face of the teeth above to 45 form a shoulder.

2. A countersink for wood having its cutting end coned and provided with teeth disposed in two sections those in the section 50 next the end being formed with their advancing or cutting face making a relatively sharp angle with the surface of the countersink, the teeth upon the section adjoining having their advancing face at a relatively 55 flatter angle with the surface of the countersink, the surfaces of the teeth in both sections continuing as planes to intersections forming shoulders.

3. A countersink attachment for bits having 60 its end formed as two frustums of cones, the end frustum having a greater angle with the axis than the section inward therefrom, both sections being provided with teeth having coincident outer edges, the teeth upon 65 the end frustum having their advancing face at a relatively sharper angle than those upon the inner frustum, and with the inner end of this face extending up into a side of a tooth of the section above.

JOHN WHYTE.
